(57) **CLAIM**

I claim the new ornamental design of a fishing rod holder for a bicycle, as shown and described.

DESCRIPTION

FIG. 1 Side perspective view of a cutting board attached to the tubular fishing rod holder for a bicycle installed on a bicycle seat post.

FIG. 2 Top perspective view there of; and,

FIG. 3 Bottom perspective view there of.

The broken line shown illustrate the environment of the fishing rod holder for a bicycle that forms no part of the claimed designed.
